(57) **CLAIM**

The ornamental design for a pizza order display panel with a transitional graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image in a sequence for a pizza order display panel with a transitional graphical user interface;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the transitional image sequentially transitions between the images shown in FIGS. 1-6. No ornamental design is shown.

(Continued)

mental aspects are associated with the process or period in which one image transitions to another image. The outermost broken line rectangle shows the pizza order display screen, and forms no part of the claimed design.
